UNITED STATES PATENT OFFICE

MELL D. SMITH, OF DE LAND, FLORIDA

ORCHARD-HEATING STOVE

Application filed May 24, 1928. Serial No. 280,311.

5 My invention relates to a heating stove for orchards and has for its object the provision of a device of the character designated which shall be simple and economical of construction and which may be readily disassembled and be packed in a small space for storage purposes.

10 A further object of my invention is to provide a stove of the character designated with a simple effective anchorage whereby it may be capable of withstanding high winds without being blown over.

15 A still further object of my invention is to provide an orchard stove with a readily mountable and demountable fuel burning or furnace section which may be filled at a storehouse away from the orchard and used to replace other similar sections in which the fuel has been burned out in the orchard, thereby obviating the necessity of refilling the stove in place in the orchard.

20 Orchard heating stoves, as heretofore known to me, have comprised a base, which included a grate, having a suitable number of legs for supporting it on the ground. Mounted upon the base were a fuel burning section and a flue. Among the difficulties which have been encountered with stoves of the prior art, the base and its legs have ordinarily been constructed of cast iron from which the legs were easily broken off in handling, rendering the base useless.

25 Another difficulty has been in anchoring the base so that the stove could withstand high winds which are usually prevalent in orange groves during periods of low temperature. This difficulty of anchorage has often led to stoves being overturned and rendered useless when most needed.

30 A still further difficulty with stoves of this character has been in the refueling thereof after burning when further heat was required. It has been necessary, with stoves of the prior art, to haul the fuel to the stoves and refill them in place. As the principal fuel usually consists of coke, which is hard to kindle, it was necessary to haul coke and kindling to the stoves, then empty out the 35 ashes from the previous burning and refill

with fresh fuel and kindling, all of which required considerable time.

In accordance with my invention, I provide a stove wherein the initial cost of manufacture is greatly reduced, wherein simple, effective, and practically unbreakable anchorage is provided, and one in which spare fuel burning sections may be readily filled away from the orchard, while a charge is being burned, and which may be set in place and ignited simply by lifting the empty fuel burning section off the base and replacing it with a filled section ready to be ignited.

These and other beneficial results are obtained with apparatus made in accordance with my invention and illustrated in the accompanying drawings, forming a part of this application, wherein

Fig. 1 is an elevational view of my improved orchard heater;

Fig. 2 is a sectional plan view taken long the line II—II of Fig. 1;

Fig. 3 is a fragmentary sectional view taken along the line III—III of Fig. 1; and

Fig. 4 is a view of a fueling section blank before being formed to fit the base.

Referring to the drawings, I show a stove comprising a flue section 10, a fuel burning section 11 and a base 12. The base 12 is made of cast iron and has formed thereon a suitable number of lugs 13 for the reception of wrought iron supporting legs 14.

Preferably, the legs 14 are cast into the lugs 13 and are each provided with a flattened portion 15 to prevent their turning in the lugs. Each of the legs 14 is provided with a flattened foot 16 adapted to rest on the sand in the orchard and to have sand banked up over it, thereby providing a firm anchorage for the stove and rendering it capable of withstanding high winds without being overturned. The provision of the wrought iron legs is a very important one in that they are not subject to breakage from handling and may be ready bent to the desired position to support the stove. They are furthermore important in that the bases may be shipped or stored with the legs flattened out and thus occupy a minimum of space.

The base is made cylindrical in form, as

shown, and is provided with a smooth tapering bore 17 to receive the lower end of the fuel burning section 11, which latter is made of ordinary sheet iron and is crimped along its lower edge at 18, the better to adapt it to fit within the bore 17.

The fuel burning section 11, as shown in Fig. 4, is made from a sheet of metal and formed with oppositely bent over edges 19 and 21 which may be interlocked upon assembly to form the longitudinal joint 22 of the assembled section. At intervals along the sheets are provided triangular slits forming tongues 23, 24 and 26, the latter tongue being larger than the other two. These tongues are bent inwardly and downwardly when the stove is assembled to form grate supporting lugs as shown at 27 in Fig. 3, and upon which rests a circular grate 28. The tongue 26 is made larger than the other two to provide, when bent inwardly, an opening 29 for readily igniting the fuel in the section 11 when desired. The fuel burning section, being made of light weight sheet metal, may be inexpensively replaced when burned out.

The flue section 10 is the same diameter as the fuel burning section 11 and is made from sheet metal similar to the section 11 and is fitted thereover stove-pipe fashion.

In using my improved stove, the legs 14 and feet 16 are bent as shown in Fig. 1 and sand is banked up around the legs and around the base except for an opening on the windward side to provide air beneath the grate 28.

The fuel burning section 11 is charged with kindling, such as the waste resinous product of turpentine stills, a layer of charcoal and then a charge of coke to fill the section 11.

The section 11 is set in the base as shown in Fig. 3 and the flue section 10 placed in position. The kindling may then be ignited by a torch through the opening 29 and the stove will burn for a considerable length of time

before burning out. While the stoves are burning, spare fuel burning sections 11 may be filled at a point remote from the orchard and brought to the orchard to replace the burned out sections without a loss of time.

From the foregoing it will be apparent that I have devised an improved orchard heating stove which is simple of design, economical of manufacture and easy of assembly and disassembly. It will furthermore be apparent, with my improved stove, that material savings in operation and a materially increased reliability in service is effected.

While I have shown my invention in but one form, it will be obvious to those skilled in the art that it is not so limited but is susceptible of various changes and modifications, without departing from the spirit thereof, and I desire therefore that only such limitation shall be placed thereupon as are

imposed by the prior art or as are specifically set forth in the appended claim.

What I claim is:

In an orchard heating stove comprising a base, a flue section and a fuel burning section supported by the base, means for detachably mounting the fuel burning section on the base, a plurality of tongues formed in the wall of the fuel burning section, said tongues being bent inwardly and then bent outwardly and downwardly to engage the wall of the fuel burning section to form grate supporting lugs, and a grate resting on the lugs.

In testimony whereof I affix my signature.

MELL D. SMITH.
